UNITED STATES PATENT OFFICE.

HERBERT L. JOHNSTON, OF TROY, OHIO, ASSIGNOR TO THE HOBART MANUFACTURING COMPANY, OF TROY, OHIO, A CORPORATION OF OHIO.

GLASS HOPPER.

Application filed November 3, 1923. Serial No. 672,586.

This invention relates to closures for glass hoppers, and the like. Hoppers of this character are quite generally used in connection with coffee grinding machines, and similar pieces of apparatus. These coffee grinding machines are very often provided with glass hoppers, to hold the coffee which is to be ground; this construction adding to the attractive appearance of the machine, and also having a utilitarian value in that the operator can observe the contents of the hopper during operation of the machine.

A hopper of this sort is of course provided with a cover or closure member, and this is usually of polished metal and one of the principal objects of this invention is to provide means for mounting a metal, or other, cover upon a hopper composed of glass, or other material to which an ordinary hinge or the like may not be readily attached.

Another object of the invention is to provide means for attaching a cover to a glass hopper, which is simple in construction, easily applied, adapted for tight and strong connection with the glass hopper without danger of breaking that hopper.

Other objects and advantages will be apparent from the description thereof set out below when taken in connection with the accompanying drawing.

In the drawing, in which like characters of reference designate like parts throughout the several views thereof;

Fig. 1 is a fragmentary sectional view through the upper part of a glass hopper, and metal closure therefor, and the means for attaching the closure to the hopper; and

Fig. 2 is a fragmentary plan view showing the closure attaching means.

This means of attaching one member to another is of quite general application, but as illustrating a preferred embodiment it is shown, as stated above, in connection with a glass hopper. This glass hopper, the upper part of which is shown in the drawing, is designated by the numeral 10, and around the top thereof it is provided with an enlargement or rib 11. It is also provided with an upwardly extending flange 12, around the mouth thereof, which flange is adapted to receive a cooperating flange carried by the closure member 13.

This closure member is preferably of polished metal, and is also preferably of thin metal which may be spun into the shape de-

sired. Of course this member may be of any other suitable material.

This closure or cover 13 has to be so arranged that it may be readily moved to uncover the mouth or inlet opening of the hopper. Also, because of the considerable vibration during operation of the device, this cover should be firmly attached to the hopper so that noise will be prevented.

In order to accomplish this connection a split ring 20 is utilized, which has its upper edge overturned as shown by the numeral 21 and its lower edge also overturned as shown by the numeral 22, to provide a channel to receive the enlargement or rib 11. The opposed ends of the split ring are provided with lugs or ears 25, these two ears having aligned passages therein adapted to receive a threaded bolt or screw 26, manipulation of which will draw the two ears together to clamp the ring firmly about the enlargement 11. Of course this split ring must be made of a somewhat flexible or elastic material, but at the same time one which has sufficient rigidity so that the overturned edges thereof will hold the ring tight about the enlargement 11. As shown each end of the ring is provided with a reinforcing member 27, each of which is firmly attached to its respective end of the ring. These may be attached in any desired manner, but as shown they are soldered or welded. These reinforcing members have attached thereto the ears 25.

Also each of these reinforcing members has attached thereto an upstanding lug or hinge member 30, which are adapted to receive cooperatively the hinge members 31, which are provided with aligned passages, while the two hinge members 31 are also provided with aligned passages, the construction being such that the passages in the two sets of members may be positioned in alignment to receive a hinge pin 32, one end of which is threaded for engagement within one of the hinge members 31. As shown hinge members 31 are also mounted upon a reinforcing member 33, which is attached to the cover by welding or soldering, although any other suitable means of attachment may be used.

The hinge members 31 are extended, as shown at 34, so that after the cover has been swung a proper distance, in opening movement, this extension will contact with the

reinforcement 27, or other fixed part of the hopper, to prevent further opening movement of the cover.

By means of this construction the cover 5 or closure may be readily mounted, in hinged relationship, upon the top of the hopper; and a neat, strong, rigid and quiet connection is attained without danger of breaking the glass of the hopper. Also this construction lends itself to cheapness of manufacture for it is not necessary that the split ring be made with any considerable degree 10 of accuracy since sufficient adjustment is provided to compensate for any irregularity of size in either the ring or the enlargement 15 11.

While the form of apparatus herein described constitutes preferred embodiment of the invention, it is to be understood that the 20 invention is not limited to this precise form of apparatus, and that changes may be made therein without departing from the scope of the invention which is defined in the appended claims.

What is claimed is:

1. Apparatus of the character described comprising a hopper of frangible material such as glass or the like, an enlargement about the top of said hopper; a flexible split 30 ring mounted on said hopper and about the said enlargement, overturned edges on said ring to receive said enlargement, means for drawing the ends of said ring together to clamp said ring firmly about the said enlargement, a hinge member carried by said ring independent of the means for clamping the ring about the enlargement; a cover for 35 said hopper, and a hinge member carried by said cover and pivotally connected to the hinge member on the said ring.

2. Apparatus of the character described comprising a hopper of frangible material such as glass or the like, an enlargement about the top of said hopper; a flexible split 45 ring on said hopper, overturned edges on said ring to receive the said enlargement between them, an ear carried by each end of said ring, means for drawing said ears toward each other to clamp said ring about the enlargement, a hinge member independent of said ears carried by each end of

said ring; a cover for said hopper, a hinge member carried by said cover and extending between the hinge members carried by the ends of said ring, and means for pivotally connecting the said first and second named hinge members. 55

3. Apparatus of the character described comprising a hopper of frangible material such as glass or the like, an enlargement 60 about the top of said hopper; a flexible split ring mounted on said hopper and having overturned edges to receive the said enlargement between them, a reinforcing member rigidly secured to each end of said ring, an ear carried by each of the said reinforcing members, a bolt for drawing the said ears toward each other to decrease the diameter of the said split ring and clamp it tightly 65 about said enlargement, a hinge member 70 carried by each of said reinforcements; a cover for said hopper, a hinge member carried by said cover and adapted for positioning between the hinge members carried by the said reinforcements, a hinge pin for positioning within aligned passages in the said 75 several hinge members, to hingedly connect the said cover to the split ring; the hinge member mounted upon the said cover being provided with an extension adapted to contact with the said reinforcing members to limit the opening movement of the said 80 cover.

4. A closure for a receptacle of frangible material such as glass or the like, comprising a flexible split ring adapted to be positioned about the receptacle, a reinforcing member rigidly secured to each end of said ring, an ear carried by each of the said reinforcing members, means for clamping said 85 ears together and adapted to draw said ring tightly about the receptacle, a hinge member carried by said ring independent of said clamping means, a cover member adapted to fit the receptacle, a hinge member carried by 90 said cover, and means for pivotally connecting said first and second-named hinge members. 95

In testimony whereof I hereto affix my signature.

HERBERT L. JOHNSTON.
